UNITED STATES PATENT OFFICE.

FRANK L. BURROWS, OF CRANSTON, RHODE ISLAND, ASSIGNOR TO DUTEE WILCOX, OF PROVIDENCE, AND CHARLES A. WILKINSON, OF WARWICK, RHODE ISLAND.

SPECTACLE-FRAME.

SPECIFICATION forming part of Letters Patent No. 606,272, dated June 28, 1898.

Application filed November 10, 1897. Serial No. 658,031. (No model.)

To all whom it may concern:

Be it known that I, FRANK L. BURROWS, of the town of Cranston, in the county of Providence and State of Rhode Island, have invented a certain new and useful Improvement in Spectacle-Frames; and I declare the following to be a specification thereof, reference being had to the accompanying drawings.

10 Like letters indicate like parts.

Figure 1 is a perspective view of the eye-rim of a spectacle-frame provided with end pieces and the clamping-screw to hold them together, between which end pieces a temple-arm is pivotally mounted. Fig. 2 is a view, partly in elevation and partly in section, on line $\alpha\alpha$ of Fig. 1 and shows the end pieces of the eye-rim secured together by the clamping-screw and also the temple-arm screw-threaded and tapped near its inner end and held between the outer portions of the end pieces by means of a screw-pivot engageable with the temple-arm and passing loosely through a perforation in one end piece and 25 into a socket of the other end piece.

My invention relates to spectacle-frames, and more particularly to the means of pivotally mounting the temple-arm between the end pieces of the eye-rims; and it consists in 30 the combination, with an eye-rim having two end pieces adapted to meet and lie in contact, whose outer portions are cut away to form a slot between them, of a temple-arm having its inner end thinned and tapped for the reception of a pivot-screw engageable therewith, which screw passes loosely through a perforation in one end piece and has its end loosely held in an interior socket of the other end piece, said temple-arm being arranged to 35 lie between the cut-away portions of the end pieces and said end pieces being secured in position together by means of a clamping-screw, as hereinafter more particularly described.

40 In the drawings, A indicates the eye-rim of a spectacle-frame adapted to hold the lens B therein. The eye-rim A has secured thereto at its two ends the earpieces a b , which are bored and tapped, as shown in Fig. 2, for the 45 reception of the clamping-screw C, which passes through both said end pieces, as shown,

and serves to hold them snugly in contact in the usual and well-known manner. Each end piece at its outer portion is thinned or cut away, as shown in Fig. 2, to form an interior slot or space wherein the temple-arm may be swung. The end piece a has a socket or recess on its inner surface, as plainly seen in Fig. 2, and the end piece b has an exterior socket or recess of the peculiar form shown in 55 said figure, where it is seen that the recess is circular as seen from without, but has a convex bottom. A perforation extends centrally from said circular socket through the bottom thereof to the inner surface of the end piece b . 60

The temple-arm D is of the usual construction and has its inner end thinned so as to enter the slot formed between the exterior portions of the end pieces a b . The temple-arm D has its eye tapped or screw-threaded, 70 as shown. A screw-pivot E passes through the perforation of the end piece b and the screw-threaded eye of the temple-arm into the socket of the end pieces a . Said screw E has its shank loosely mounted in the perforation of the end piece b , and its threads engage the threaded eye of the temple-arm D, and its point enters loosely into the socket of the end piece a . The head of the screw E is enlarged and is contained in the tubular 75 socket of the end piece b and bears against the convex bottom of said socket. By means of this construction it is possible to remove the temple-arm D from the end pieces a b without separating said end pieces, thus allowing such adjustment without removal of the lens B from the eye-rim A, the clamping-screw C always serving to hold the end pieces together and confine the lens in the frame. By unscrewing the screw-pivot E the 80 temple-arm can be readily taken out and can be inserted again by inserting the screw E as before. The convex bottom of the tubular slot of the end piece b serves as a bearing to receive the pressure of the screw-head, 85 upon the inner side thereof. The points of contact between said rounded or convex bottom of said socket and the inner surface of the screw-head being very limited in extent the frictional bearing is very light. 90

When the temple-arm D swings, the screw-pivot E, which is engaged with it by the 95

screw-threads, turns with it, such movement of the screw being possible because the screw passes loosely through one end piece and into the socket of the other without engaging with either. By slightly turning the screw E the friction of the temple-arm may be easily regulated.

Besides the great advantage of the easy detachability of the temple-arm from said end pieces by the construction shown I also secure the advantage of a comparatively-extended bearing-surface not only between the end pieces, but also through the whole extent of the screw E, which serves as a pivot.

15 Heretofore, so far as I am aware, temple-arms have always been provided with a plain hole or eye and have loosely swiveled upon a pivot, screw-shank, or dowel, which itself is stationary; but my invention is new in that 20 my temple-arm has an eye screw-threaded and the screw-pivot engages by this means with the temple-arm and turns with it.

By the use of the inner socket in the end piece *a* to receive the point or end of the 25 screw E the exterior surface of the outer portion of the end piece *a* is not perforated, but plane, and so is not disfigured and is capable of a superior finish.

I claim as a novel and useful invention and 30 desire to secure by Letters Patent—

1. The combination in spectacle-frames, having an eye-rim with end pieces secured thereto and adapted to meet each other and which are thinned at their outer portions, of

a clamping-screw passing through said end 35 pieces, a slot between the outer cut-away portions of the end pieces, a socket or recess in the inner surface of one end piece, a socket in the outer surface of the other of said end pieces, a perforation through said end piece 40 last mentioned, concentric with said socket, a temple-rim having a screw-threaded eye, and a screw-pivot passing through the last-named end piece and into the socket of the other end piece and engaging with its thread 45 said temple-arm, substantially as specified.

2. The combination in spectacle-frames, having an eye-rim with end pieces secured thereto adapted to meet each other and which are thinned at their outer portion, of a clamping-screw passing through said end pieces, a slot between the outer cut-away portions of the end pieces, a socket or recess in the inner surface of one end piece, a tubular socket with convex bottom formed in the other of 55 said end pieces and opening exteriorly, a perforation through said convex end of the last-named socket and concentric therewith, a temple-arm having a screw-threaded eye, and a screw-pivot passing through the socket and 60 perforation of the last-named end piece and engaging with its thread said temple-arm, substantially as shown.

FRANK L. BURROWS.
